[57] CLAIM

The ornamental design for recycling container for mounting to a wastebasket, as shown and described.

DESCRIPTION

FIG. 1 is a front elevational view of a recycling container for mounting to a wastebasket showing our new design, the rear elevational view being a mirror image of that shown;

FIG. 2 is a left side elevational view thereof;

FIG. 3 is a right side elevational view thereof;

FIG. 4 is a top plan view thereof;

FIG. 5 is a bottom plan view thereof;

FIG. 6 is a top perspective view thereof showing the container placed in the interior of a wastebasket, the broken lines are for illustrative purposes only; and,

FIG. 7 is a top perspective view thereof showing the container placed on the exterior of a wastebasket.

FIG 1

FIG 2

FIG 3

FIG 4
